CLAIM

The ornamental design for a roller stamp, as shown and described.

DESCRIPTION

FIG. 1 is a top perspective view of a roller stamp showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded top plan view of a roller stamp showing my new design.

Broken lines in the drawings depict portions of the roller stamp that form no part of the claimed design.

1 Claim, 6 Drawing Sheets
